[57] CLAIM

The ornamental design for a container carrier, as shown and described.

DESCRIPTION

FIG. 1 is a right, top and front perspective view of a container carrier showing my new design;

FIG. 2 is a front view thereof;

FIG. 3 is a left side view thereof, with a container being shown in broken lines for illustrative purposes only and forming no part of the claimed design;

FIG. 4 is a left side view;

FIG. 5 is a right side view thereof;

FIG. 6 is a top view thereof;

FIG. 7 is a bottom view thereof;

FIG. 8 is a rear view thereof; and,

FIG. 9 is a right, top and front perspective view of a second embodiment, all other views being identical to FIGS. 1-8 except for the removal of the strap connector.

1 Claim, 8 Drawing Sheets
